[57] CLAIM

The ornamental design for a control housing for an
electric blanket, as shown.

DESCRIPTION

FIG. 1 is a front and top-right perspective view of a
control housing for an electric blanket showing our new
design;

FIG. 2 is a left side elevational view thereof;

FIG. 3 is a top plan view thereof;

FIG. 4 is a front elevational view thereof;

FIG. 5 is a right side elevational view thereof;

FIG. 6 is a bottom plan view thereof;

FIG. 7 is a rear elevational view thereof.

The power cord of FIG. 1 is omitted from FIGS. 2-7
for ease of illustration.

FIG. 7.

FIG. 6.

FIG. 5.

FIG. 3.

FIG. 4.

FIG. 1.

FIG. 2.
